UNITED STATES PATENT OFFICE.

ANDREW F. HOWE, OF GRANITE CITY, ILLINOIS.

WHEEL-TEMPERING APPARATUS.

SPECIFICATION forming part of Letters Patent No. 736,103, dated August 11, 1903.

Application filed September 25, 1902. Serial No. 124,770. (No model.)

To all whom it may concern:

Be it known that I, ANDREW F. HOWE, a citizen of the United States, residing at Granite City, Madison county, Illinois, have invented 5 a certain new and useful Improvement in Wheel-Tempering Apparatus, of which the following is a full, clear, and exact description, such as will enable others skilled in the art to which it appertains to make and use 10 the same, reference being had to the accompanying drawings, forming part of this specification, in which—

Figure 1 is an elevational view partly in section. Fig. 2 is a plan and sectional view, 15 and Fig. 3 is a front elevational view of the apparatus looking toward the heating chamber or furnace.

The object of the invention is to produce 20 an apparatus designed especially for tempering the rims of car-wheels, though it may be used for tempering other articles; and it consists in features of construction and combination of parts, all as hereinafter more fully described, and specifically pointed out in the 25 claims.

Referring to the drawings, A is a suitable base upon which is erected a heating-chamber 1, formed with an opening 2 in the front portion thereof, to which opening there are applied 30 the doors 3 and 4. To the upper portion of door 3 are connected chains 5, which are secured thereto by means of the eyes 6, while corresponding eyes 6 upon the lower door 4 are used to connect said chains at the 35 lower ends. Said chains pass over sheaves or pulleys 7, whereby said doors are balanced, while the weight 8, connected to the chain or rope 9 and to said door 3 by means of the loop or eyelet 10 and passing over the sheaves 40 11, also counterbalances said doors and aids in opening the same, said sheaves 11 being supported above the heating-chamber by brackets 12, as shown. It will be understood that the heating-chamber, or so much thereof 45 as comes into contact with the products of combustion, is built of refractory material, such as fire-clay, &c. Connected at the upper left-hand end of the heating-chamber is a burner 13, (represented conventionally,) 50 which burner is adapted by means of a blast to project a flame into and through the flue 14 of said heating-chamber, which flue follows a circular path, preferably about the diameter

of a car-wheel, whence it turns and extends upwardly, as shown, so as to connect with a chimney-flue, (not shown,) by which is carried off the spent products of combustion. The curved flue 14 is inclosed upon all sides, so that no flame will impinge the rim of the wheel or any article contained within said furnace, though the intense heat introduced within said flue will quickly heat any article introduced into said chamber. In convenient proximity to said heating-chamber, upon a suitable base B, is a supporting-table composed of the legs 16, braces 17, and supporting-blocks 18, to which latter are connected the rectangular track-rails 19, extending longitudinally at each side of said table. Resting upon and partly inclosing said rails 70 are plates 20, to which are bolted flanged extensions 21 of collars 22, within which latter is held the revoluble shaft 23, which latter is larger, preferably, within said collars and has upon its outer (the left-hand) end a sprocket-wheel 24, adapted to be driven from any suitable source of power (not shown) for the purpose of revolving said shaft. The enlargements 25 of the shaft 23 may be integral therewith or may consist of collars 8c shrunk in place, and thereby held fast to said shaft. Near the furnace end of said shaft 23 and either integral therewith or secured thereto is a double-coned member provided with the coned face 26, shoulder 27, and retreating face 28, the face 26 being adapted to enter the axle-opening of a car-wheel 32, which car-wheel will abut against the shoulder 27, while a second conical member 29 is placed upon the end portion of the shaft adjacent thereto, where it is held by the nut 30, screwed upon the projecting portion 31 of said shaft, whereby the wheel is clamped in position. 85 90

Between the heating chamber or furnace 95 and the base B is a depression or well, within which is located a hydraulic or other operable lifting device 33, which carries a receptacle 34, movable vertically and guided in its movements by suitable guide-rods 35. Within said receptacle 34 may be placed any suitable tempering-vehicle, such as oil, and when the wheel has been sufficiently heated within the furnace it is withdrawn to a point above the receptacle 34, said receptacle is elevated 100 105 by any suitable means, (not shown,) and the

rim is immersed in the tempering liquid therein, during which immersion the wheel is rapidly revolved with the carrying-shaft 23, so as to quickly present its entire peripheral face to the action of the tempering liquid, which latter will be carried in thin layers upon the rapidly-revolving face of said wheel until the same is sufficiently influenced thereby, whereupon the receptacle 34 is lowered and the lever 36 is thrown back, carrying with it the link 37, connected to the under side of one of the collars 22, and retracting the carriage composed of said collars and the plates 20, to which said flanges 21 are secured. The 15 wheel and shaft in this retracted position will occupy substantially the position shown in dotted lines in Fig. 1, though it will be understood that there is sufficient clearance to permit the removal of the wheel from the 20 shaft, which is accomplished by first unscrewing said nut 30, removing said conical bearing member, after which the wheel is readily removable. Owing to the intense heat produced by the blast within said flue it is de- 25 sirable to have as large a working opening on the rear side of the furnace as possible to afford ready access to the members on that end of shaft 23, so I there provide the circular opening 38, through which access is af- 30 forded to the nut 30 when desired for manipulating the same. Said lever 36 is pivotally connected at 40 to the arm 41, which in turn is pivotally held within the yoke 42, so that the lever is free to operate to advance 35 or retract the shaft 23, as desired. The driving-sprocket 24 is supported in position and fast to the collar 44, which latter is provided with a circumferential way or channel 45, in which is held the yoke 46 of the bracket 47, 40 while a key 48 projects into a longitudinal groove 49, formed in said shaft 23, whereby independent longitudinal movement of the shaft is permitted while being driven from a fixed source of power, as shown in Fig. 1 in 45 dotted lines.

I am aware that many minor changes in the construction, arrangement, and combination of the several parts of my device can be made and substituted for those herein shown and 50 described without in the least departing from the nature and principle of my invention.

Having thus described my invention, what I claim as new, and desire to secure by Letters Patent, is—

55 1. In an apparatus for tempering the rims of wheels, revolute means for supporting the wheels, and means for moving the same longitudinally; substantially as described.

2. In an apparatus for tempering the rims 60 of wheels, revolute supporting means in line with a heating-chamber, and means for moving the same in the line of its axis; substantially as described.

3. In an apparatus for tempering the rims 65 of wheels, a revolute and slideable support, and a heating-chamber in line therewith; substantially as described.

4. In an apparatus for tempering the rims of wheels, a power-driven carrying means movable longitudinally of its axis, and a heating-chamber in the line of movement thereof; substantially as described. 70
5. An apparatus for tempering the rims of wheels comprising power-driven supporting means movable longitudinally, heating-chamber, and tempering-bath receptacle, all combined substantially as described. 75
6. An apparatus for tempering the rims of wheels comprising a heating-chamber, a tempering-bath receptacle, and power-driven revolute supporting means movable with relation thereto; substantially as described. 80
7. In an apparatus for tempering the rims of wheels, a heating-chamber, a tempering-bath receptacle, and revolute supporting means in proximity thereto; substantially as described. 85
8. In an apparatus for tempering the rims of wheels, a heating-chamber, movable doors therefor, a tempering-bath receptacle, and revolute supporting means in proximity thereto; substantially as described. 90
9. In an apparatus for tempering the rims of wheels, a heating-chamber, a movable tempering-bath receptacle, a revolute supporting means in proximity thereto; substantially as described. 95
10. In an apparatus for tempering the rims of wheels, a heating-chamber, a vertically-movable tempering-bath receptacle, and revolute supporting means in proximity thereto; substantially as described. 100
11. In an apparatus for tempering the rims of wheels, a heating-chamber, a tempering-bath receptacle, and revolute supporting means in proximity thereto and movable from said heating-chamber; substantially as described. 105
12. In an apparatus for tempering the rims of wheels, a heating-chamber, a tempering-bath receptacle, and revolute supporting means in proximity thereto and movable from said bath-receptacle; substantially as described. 110
13. In an apparatus for tempering the rims of wheels, a heating-chamber, a tempering-bath receptacle, revolute supporting means in proximity thereto, and means for moving said support with relation to said heating-chamber; substantially as described. 115
14. In an apparatus for tempering the rims of wheels, a heating-chamber, a tempering-bath receptacle, revolute supporting means in proximity thereto, and means for moving said support longitudinally with relation to said heating-chamber; substantially as described. 120
- 125

In testimony whereof I hereunto affix my signature, in the presence of two witnesses, this 23d day of September, 1902.

ANDREW F. HOWE.
